UNITED STATES PATENT OFFICE

107,663

DESIGN FOR A CORDED KNIT LACE FABRIC

Samuel Saftlas, New York, N. Y., assignor to Selig Kaplan and Julius Kaplan, co-partners doing business under firm name and style of Pennant Knitting Mills, Brooklyn, N. Y.

Application October 15, 1936, Serial No. 65,308

Term of patent 3½ years

To all whom it may concern:

Be it known that I, Samuel Saftlas, a citizen of the United States, residing at New York city,
in the county of Kings and State of New York,
have invented a new, original, and ornamental Design for Corded Knit Lace Fabric, of which the following is a specification, reference being had to the accompanying drawing, forming a part thereof.

The figure of the drawing is a face view of the

corded knit lace fabric showing my design.

The characteristic feature of the design resides in the design and arrangement of the heavy threads superposed on a basic open net fabric
as shown.

I claim:

The ornamental design for a corded knit lace
fabric substantially as shown and described.

SAMUEL SAFTLAS.
